UNITED STATES PATENT OFFICE.

ERNEST J. KNABE, JR., OF CINCINNATI, OHIO.

COUPLER FOR MUSICAL INSTRUMENTS.

1,169,654.

Specification of Letters Patent. Patented Jan. 25, 1916.

Application filed February 13, 1915. Serial No. 8,106.

To all whom it may concern:

Be it known that I, ERNEST J. KNABE, Jr., a citizen of the United States, residing at Cincinnati, in the county of Hamilton and State of Ohio, have invented certain new and useful Improvements in Couplers for Musical Instruments; and I do hereby declare the following to be a full, clear, and exact description of the invention, such as will enable others skilled in the art to which it appertains to make and use the same.

My invention relates to couplers for musical instruments of the type in which more than one bank of keys is used.

The objects of my invention are: to produce a coupler for use with more than one bank of keys, in which the keys and coupler will be so constructed and arranged that the operation of a key in one of the banks will sound the strings, pipes or reeds controlled thereby and may cause the sounding of the strings, pipes or reeds controlled by a key in another bank depending upon whether the coupler is used or not; to produce a coupler for use with a key-board having more than one bank of keys so constructed and arranged that the touch will be substantially the same, whether said connections are so set that a key in one bank controls only its corresponding strings, pipes or reeds, or whether said connections are shifted so that said key also controls the strings, reeds or pipes corresponding to a key in another bank; to produce a coupler for accomplishing the above specified objects which will be simple, easy of adjustment and reliable in operation.

I shall now describe my improved coupler as constructed and arranged for use in a combined string and wind instrument, such as a combined piano and organ.

In the drawings:—Figure 1 is a side elevation of my improved key-board as constructed with two banks of keys; Fig. 2 is a plan view of the parts shown in Fig. 1, the key bottom being omitted; Fig. 3 is a side elevation of some of the parts shown in Fig. 1, the connection being shifted and the key bottom omitted; Fig. 4 is a plan view of some of the parts shown in Fig. 2; Fig. 5 is a section of one key and also shows part of one shiftable connection, the full lines corresponding to the position of the button 33 as shown in Fig. 3 and the dotted lines to the position of said button as shown in Fig.

1; and Fig. 6 is a plan view of the parts shown in Fig. 5.

1 represents a key bottom which may be of any approved construction and suitably supported, so that the keys will be in a proper location for operation by the hands of the performer.

2 and 3 represent key frames of any approved constructions, the latter being supported upon the key frame 2 by supports, two of which are shown at 4, 4. The key frames 2 and 3 are provided with the usual balance pins and felt washers therefor, balance rails, front pins and felt washers therefor, and the key pads 5 and 6 respectively.

The key 7 is provided with the usual capstan screw 8^a upon which rests the abstract 9^a. The lower portion only of the abstract 9^a is shown. The abstract, the piano action of which it forms a part and the other parts of the piano being of any approved, or of the well known construction will not be described.

The key 8 is normally held in the position shown in Fig. 1 by the spring 9 which is secured by the screws 12 to the cross piece 10, and the latter is secured to the key frame 3 by supports, one of which is shown at 11.

The spring 14 is attached to the key 8 by the screws 13 and on the under side of the free end of said spring there is secured a valve disk 15. The valve disk 15 normally closes the port 16 in the cross piece 29 (see Figs. 3 and 4), and the latter is connected with the duct 17. The cross piece 29 extends entirely across the key-board, and is supported on the key frame 2, one support being shown at 30. The cross piece 29 is provided with one port similar to 16 and one duct similar to 17 for each key in the upper bank. The duct 17 is to be connected to a suitable pneumatic mechanism for controlling the flow of air to pipes or reeds, the whole being so arranged that when the valve disk 15 is lifted from the port 16, then said pipes or reeds will sound. This pneumatic mechanism and said pipes or reeds being of any approved, or of the well known construction will not be described.

In the construction above described when the front end of the key 7 is depressed, as shown by dotted lines in Fig. 1, the abstract 9^a is raised and the hammer of the piano action, is caused to strike the strings. Similarly, the depression of the front end of the

key 8 will raise the valve disk 15 from the port 16 and cause the corresponding pipe or reed to sound. That is, the keys of each bank will sound their corresponding sounding devices only. But it is sometimes desirable to sound the organ by the movement of the piano key. The instrumentalities whereby this effect can be obtained at the will of the performer will now be described.

10 Recesses 18 and 19 are cut in the inner side of the key frame 3 and in these recesses the flanges 20 and 21 are secured. Links 22 and 23 are articulated with the flanges 20 and 21 by pins 24, 24, and with the rail 25 by the pins 26, 26. The rail 25 is supported on the hooks 27, and the latter are screwed into the key frame 3. A rail 28 is secured to the cross piece 29 and projects a short distance to the right of the latter as shown in Fig. 1. Bushings 31, 31, are provided in the rails 25 and 28 and a wire 32 slides freely in said bushings. The rails 25 and 28 extend the full width of the key-board and there are as many wires similar to 32 mounted therein as there are keys in the upper key-board. The rail 25 is to be connected in any approved manner with a pedal, knee swell, hand operated lever or draw knob, so that the performer can at will move its ends 25 in either direction as along the dotted lines 45, 45 in Fig. 4. One way of moving the rail 25 is shown in Fig. 4, in which 47 is a hand operated lever, articulated as at 48 to a support 49 fixed to the key frame 3 and as at 50 to the rail 25. Wood buttons 33 and 34 are screwed, respectively, on the threaded lower and upper extremities of the wire 32 and the hemispherical outer ends of said buttons are provided with leather buffers 35 and 36 respectively. When the parts are in 30 the position shown in Fig. 1, the top of the buffer 36 is slightly below the spring 14 and the bottom of the buffer 35 is just above the top surface 37, (see Fig. 1) of the step 38.

35 The step 38 which is approximately the same width as the key, is rigidly secured to the top of the key 7. The front surface 39 and the rear surface 40 of the step 38 are substantially parallel to each other and at 40 right angles to the top and side surfaces of the key 7, (see Figs. 5 and 6). The top surface 37 of the step 38 is slightly inclined to the top surface of the key 7 as shown in Figs. 1 and 3, and the surface 41 is inclined to both 45 of the surfaces 37 and 40. Beginning at the lines 42 and 43 on the surfaces 37 and 41, another inclined surface 44 slopes downwardly and toward the right as shown in Fig. 5.

50 The operation of my improved key-board is as follows:—When the rail 25 is in the position shown in Fig. 3 and by the dotted lines in Fig. 4, the buffer 35 will be out of the path of the step 38. If now the front 55 end of the key is depressed, the abstract 9^a

will be lifted and the piano action operated in the usual manner, thus sounding the corresponding string of the piano, but the pipe or reed of the organ will not be sounded. If the front end of the key 8 is depressed the valve disk 15 will be lifted off the port 16 and the corresponding pipe or reed will be sounded. When the rail 25 is in the position just specified, then the piano and organ key-boards must be operated 75 separately. If now the rail (25) be moved to the position shown in Fig. 1 then the buffer 35 will be in the path of the step 38 and when the front end of the key 7 is depressed, as shown by dotted lines in Fig. 1, 80 the abstract 9^a will be lifted as before described, the buffer 36 will also lift the spring 14, as shown by dotted lines in Fig. 1, thus opening the port 16 and the corresponding pipe or reed will sound with the strings of 85 the piano. If the front end of key 8 is depressed the corresponding pipe or reed will be sounded as before described.

It is to be noted that the spring 14 is much lighter in tension than the spring 9, so that 90 the key 8 does not move when the spring 14 is lifted by the key 7, and the spring 14 is sufficiently light to avoid an appreciable change of touch when the rail 25 is moved to the position last described. Hence it is evident that the key 8 never controls more than 95 its corresponding pipe or reed, but that the key 7 may, at the will of the performer, control only its corresponding strings, or in addition thereto the corresponding pipe or reed 100 in the organ division of the instrument.

From an inspection of Figs. 1, 3, 4, 5 and 6 it is evident that even if the front end of the key 7 is depressed then the rail 25 can be moved from the position shown in Fig. 3 105 to that shown in Fig. 1, with the result that the buffer 36 will lift the spring 14, because the buffer 35 during this motion of the rail 25 will slide up the inclined surface 44, thus sounding the corresponding pipe or reed. 110 It is also evident that the rail 25 can be moved in the reverse direction while the front end of the key 7 is depressed with the result that said pipes or reeds will cease to sound.

I have stated that the key 7 is used to sound strings in a piano, and that the key 8 is used to control pipes or reeds in an organ, but these functions may be reversed, or both keys can be used for sounding strings 115 in pianos, or for controlling pipes or reeds in organs and many other changes could be made without departing from the spirit of my invention.

Thus I provide a simple and effective 125 shiftable connection between the upper and lower keys which can be used even if said lower key is depressed at its front end.

I claim:—

1. In couplers for musical instruments, 130

the combination of a lower key, an upper key, a valve moved by said upper key, a fixed rail, a movable rail, a connection between said lower key and said valve mounted to slide in both of said rail and means for moving said movable rail.

2. In couplers for musical instruments the combination of a lower key, an upper key, a spring mounted on said upper key, a valve mounted on said spring and a connection between said lower key and said spring whereby said valve can be moved without moving said upper key.

3. In couplers for musical instruments the combination of a lower key, an upper key, a spring mounted on said upper key, a valve mounted on said spring, a spring for yieldingly holding said upper key in its normal position against the stress of said first named spring, and a connection between said lower key and said first named spring whereby said valve can be moved without moving said upper key.

4. In couplers for musical instruments the combination of a lower key, an upper key, a valve moved by said upper key, a step on said lower key having a flat top and a surface inclined to said top, a fixed rail, a mov-

able rail, a connection mounted to slide in both of said rails and means for moving said movable rail so that one end of said connection will slide up said inclined plane and to said top, when the front end of said lower key is depressed.

5. In couplers for musical instruments, the combination of an upper key and key frame, a lower key and key frame, a valve mounted on said upper key, a fixed rail, a movable rail, a connection between said lower key and said valve mounted to slide in said movable and fixed rails, links each having one end pivoted to said upper key frame and the other end pivoted to said movable rail, said links having their pivoted ends so positioned that said links guide said movable rail forwardly and to one side to bring said connection into position to move said valve, and rearwardly and to the opposite side to bring said connection into a position in which it does not move said valve.

In testimony whereof, I affix my signature, in presence of two witnesses.
